UNITED STATES PATENT OFFICE

2,445,860

WINDOW PLATFORM

Elmer M. Newkirk, St. Joseph, Mo.

Application January 2, 1946, Serial No. 638,674

5 Claims. (Cl. 304—26)

1

The present invention relates to window platforms and is more particularly concerned with demountable and adjustable staging suitable for outside use in washing windows.

The primary object of the invention is to provide a demountable staging which may be readily assembled and adjusted to windows of various widths.

Another object of the invention is to provide a safe staging for window washing.

A further object of the invention is to provide a platform of the character referred to of simpler and more compact construction than is disclosed in prior devices.

With the foregoing and other objects and advantages in view, the invention consists of the novel construction and arrangement of parts hereinafter described and claimed.

In the accompanying drawings, illustrating the invention:

Figure 1 is a top plan view of the frame of the staging.

Figure 2 is a top plan view of the complete staging.

Figure 3 is a detail perspective view of one of the staging support blocks.

Figure 4 is a detail perspective view of the angle plate to which the block is fastened.

Figure 5 is a vertical section on line 5—5 of Figure 6.

Figure 6 is a side elevation of the staging in operative position on a window sill.

Like numerals are used in the drawings and description to designate the same parts of construction.

The frame proper of the staging consists of two parallel side bars 1, constructed preferably of light structural steel in the form of angle iron.

At the outer or projecting ends these two bars are connected by an adjustable cross-bar 2 of the same type of material as that in the side bars. Adjustability of the end bar 2 is attained by constructing it in two telescopic sections held together slidably by means of keeper sleeves 3 and bolting the outer ends of said sections to the side bars 1.

The opposite or inner ends of the side bars are mounted to slide longitudinally in angle plates 4 provided with channels 5 to contain the longitudinal edges thereof. These channels are formed by flanges on the inside of the element 4.

Welded or otherwise suitably secured to the plate 4 so as to depend therefrom, is a rectangular, hollow block 6, constructed of metal and provided with open sides and flat top and bottom. The two elements 4 and 6 are provided centrally with registering slots 7 for the reception of a set screw 8 which is adapted to fasten said elements to the hereinafter described cross-bar 9, when adjusted to the window opening. The same is

2

true concerning the oppositely located element 4 and attached block 6. With the foregoing construction, parallelism of bars 1 can be maintained.

Both of the blocks 6, are designed to rest on the outer portion of the window sill, as illustrated in Figure 6, and the two blocks, as well as side bars 1, are held together adjustably by a sectional cross-bar 9, the outer ends of which pass through slots 10 formed in depending lugs 11 on the underside of the horizontally-disposed part of angle plate 4. The sections of cross-bar 9 are slidably joined by means of a keeper sleeve 12, thus the width of the frame, dependent on the spacing apart of side bars 1, is adjusted to the requirements of different sized windows, by means of the two sectional cross-bars 2 and 9. The frame of the staging is secured to the inside of the window frame by means of laterals 12, projecting at right angles from the inner ends of side bars 1 and adapted to impinge the wall on the inside of the building, the bars being extended for the purpose.

The platform for the staging comprises two sections of timber, consisting of transverse boards 13 suitably spaced apart and positioned so as to permit the boards of one to slide between the boards of the other, thus effecting a lateral adjustment of width to conform to the adjustment of side bars 1 of the frame. Longitudinal strips 14 are bolted on top of the transverse boards 13 to fasten same together and the outer ends are bolted on top of longitudinally disposed beams 14a of wood or other suitable material, which are dimensioned to fit in the angle of bars 1.

Two supporting brackets 15 are slidably mounted on the underside of the side bars 1 by means of adjustable keeper sleeves 16 suitably positioned thereon to contain the ends of the said brackets. These brackets are metal and angular in shape each with a vertical leg 17 adapted to abut the outer edge of the window sill. This leg is bent inward at the upper extremity at a right angle to fit in the sleeve 16. A set screw 18, in the bottom of the sleeve, impinges the bent portion and secures this end of the bracket in its adjusted position.

The other end of each bracket is contained in a similar keeper sleeve and adjustably fastened in place by means of a set screw 18. As these brackets are designed to serve as supports for the platform when in use, the brackets will be constructed of suitable structural steel for strength and the long hypotenuse-like arm, will be sufficiently proportioned to stand the strain of the platform when a person is standing thereon.

As protective means for the worker, the staging is provided with foldable sides 19 having longitudinal guard rails and uprights, of wood or other suitable material and the whole being hinged to the board platform, as at 20, to fold inwardly. A removable rod 21, with depending

hooks on the end, is provided to fasten the sides together at their outer ends.

Having thus described my invention, what I claim as new and desire to secure by Letters Patent is:

1. A portable platform for use with a window frame having an outwardly projecting window sill, said platform comprising a pair of parallel horizontal side bars adapted to be placed through the window frame against the facing sides thereof, laterally outwardly projecting portions on the inward ends of said side bars for engaging the back of the opposite sides of the window frame, an outer cross member extending between and securable at its ends to the outer ends of said side bars, said outer cross member being adjustable lengthwise to space said side bars at the proper distance for engaging said side bars with the facing sides of the window frame, a window sill block depending from each side bar and slidably adjustable therealong to position for resting upon the window sill, and an inner cross member extending between and securable at its ends to said window sill blocks for positively maintaining said side bars in engagement with the facing sides of said window frame.

2. A portable platform for use with a window frame having an outwardly projecting window sill, said platform comprising a pair of parallel horizontal side bars adapted to be placed through the window frame against the facing sides thereof, laterally outwardly projecting portions on the inward ends of said side bars for engaging the back of the opposite sides of the window frame, an outer cross member extending between and securable at its ends to the outer ends of said side bars, said outer cross member being adjustable lengthwise to space said side bars at the proper distance for engaging said side bars with the facing sides of the window frame, a window sill block depending from each side bar and slidably adjustable therealong to position for resting upon the window sill, and an inner cross member extending between and securable at its ends to said window sill blocks for positively maintaining said side bars in engagement with the facing sides of said window frame, and means for drawing said laterally outwardly projecting portions into engagement with the back of the opposite sides of the window frame, said means comprising a brace depending from and slidably adjustable along each side bar for engaging the outer side of the sill with said laterally outwardly directed side bar portions engaged with the back of opposite sides of the window frame.

3. A portable platform for use with a window frame having an outwardly projecting window sill, said platform comprising a pair of parallel horizontal side bars adapted to be placed through the window frame against the facing sides thereof, laterally outwardly projecting portions on the inward ends of said side bars for engaging the back of the opposite sides of the window frame, an outer cross member extending between and securable at its ends to the outer ends of said side bars, said outer cross member being adjustable lengthwise to space said side bars at the proper distance for engaging said side bars with the facing sides of the window frame, a window sill block depending from each side bar and slidably adjustable therealong to position for resting upon the window sill, and an inner cross member extending between and securable at its ends to said window sill blocks for positively maintaining said side bars in engagement with the facing sides

of said window frame, a protective side hinged at its lower edge to each side bar for folding laterally inwardly and downwardly to a position between said sidebars, and a rod removably engageable at its ends with upper portions of said sides for maintaining said sides securely in vertical positions.

4. A portable platform for use with a window frame having an outwardly projecting window sill, said platform comprising a pair of parallel horizontal side bars adapted to be placed through the window frame against the facing sides thereof, laterally outwardly projecting portions on the inward ends of said side bars for engaging the back of the opposite sides of the window frame, an outer cross member extending between and securable at its ends to the outer ends of said side bars, said outer cross member being adjustable lengthwise to space said side bars at the proper distance for engaging said side bars with the facing sides of the window frame, a window sill block depending from each side bar and slidably adjustable therealong to position for resting upon the window sill, and an inner cross member extending between and securable at its ends to said window sill blocks for positively maintaining said side bars in engagement with the facing sides of said window frame, spaced platform forming elements secured only at their laterally outward ends to each side bar and extending toward the other sidebar and interleaved to provide a substantially continuous laterally expandible platform between said side bars.

5. A portable platform for use with a window frame having an outwardly projecting window sill, said platform comprising a pair of parallel horizontal side bars adapted to be placed through the window frame against the facing sides thereof, laterally outwardly projecting portions on the inward ends of said side bars for engaging the back of the opposite sides of the window frame, an outer cross member extending between and securable at its ends to the outer ends of said side bars, said outer cross member being adjustable lengthwise to space said side bars at the proper distance for engaging said side bars with the facing sides of the window frame, a window sill block depending from each side bar and slidably adjustable therealong to position for resting upon the window sill, and an inner cross member extending between and securable at its ends to said window sill blocks for positively maintaining said side bars in engagement with the facing sides of said window frame, each window sill block being formed with an aperture slidably receiving a related end portion of said inner cross member, and means for locking the ends of said inner cross member in place in said apertures.
